SPANNING-FRAME.

1,171,847.

Specification of Letters Patent.

Patented Feb. 15, 1916.

Application filed June 8, 1914, Serial No. 843,897. Renewed August 4, 1915. Serial No. 43,708.

To all whom it may concern:

Be it known that I, KARL F. JENSEN, a subject of the King of Sweden, and a resident of South River, in the county of Middlesex and State of New Jersey, have invented certain new and useful Improvements in Spanning-Frames, of which the following is a specification.

My invention relates to improvements in frames for spanning pieces of fabric, such for example, as handkerchiefs, for the purpose of holding the fabric while it is being embroidered or otherwise worked upon.

In the embroidering of handkerchiefs and the like in large numbers, it is the custom to mount a considerable number of pieces of fabric in a suitable frame, termed a "spanning frame," the frame being so constructed as to hold straight and practically rigid the particular portion of each one of the pieces of fabric which are to be embroidered or otherwise worked upon, and then the frame, or a plurality of such frames having the pieces of fabric spanned therein, is set within a suitable embroidery machine, and by the operation of such machine the same ornamental figure or other device is stitched upon each of the pieces of fabric in such frame or frames, simultaneously.

The spanning frame forming the subject matter of the present application is particularly adapted for holding the fabric near the corner; as, for example, for the working of an initial or other ornamentation near the corner; but is likewise adapted for holding the fabric at any other points than near the corners.

My invention consists in the novel spanning devices employed, in the novel means employed for locking the spanning devices, in the novel means employed for gaging the point at which the fabric is to be clamped, and in various other features as hereinafter described and more particularly pointed out in the appended claims.

The objects of my invention are to improve and simplify spanning devices; to provide improved and simplified means for locking the spanning devices together and for facilitating the unlocking of such spanning devices; to provide simple and readily adjustable means for gaging the point at which the fabric is to be spanned; and in general to produce a spanning device which

is simple in construction, and capable of being operated with ease and rapidity.

I will now proceed to describe my invention with reference to the accompanying drawings, and will then point out the novel features in claims.

In said drawings: Figure 1 shows a fragmentary top view of a portion of a spanning frame employing my invention. Fig. 2 shows a transverse section thereof on the line $x-x$ of Fig. 1; and Fig. 3 shows a fragmentary bottom view. Figs. 4-7 inclusive are detail views of parts of the spring clamp preferably employed; Fig. 4 being an elevation and partial longitudinal section of the pin of said clamp, Fig. 5 an elevation of the sleeve of said clamp, Fig. 6 an elevation of the end of one of the members 3 carrying the bushing 12, and Fig. 7 a longitudinal section of the spring gripping device 14.

My improved spanning frame comprises a plate 1, commonly and preferably formed of a metal which is at once rigid, light, not likely to soil fabric, and free from objectionable tendency to oxidation or corrosion ("Monel metal" and similar alloys are suitable for the purpose), such plate provided at suitable intervals with suitable spanning apertures 2, preferably slightly tapered as indicated in Fig. 2; and a plurality of light members 3, hinged or otherwise movably secured to the plate 1, at one end, and provided with annular flanges 4 adapted to enter the spanning apertures 2 of plate 1, as indicated particularly in Fig. 2, and also provided with suitable means for fastening down their free ends; for example, the spring clamp hereinafter described. These members 3 are also, preferably, formed of metal, and in the construction shown I have indicated these members 3 as hinged each at one end, to the plate 1, in that said members 3 are hinged to hinge blocks 5 secured to plate 1 by being recessed partly into said plate and by means of screws 6. The members 3 are preferably somewhat springy or resilient. The outer surface of each annular flange 4 conforms, preferably, somewhat closely to the aperture 2 into which it is adapted to fit, with just enough clearance from the sides of such aperture to permit the tight clamping of the fabric between the outside of the flange 4 and the sides of such aperture 2. Since the

flange 4 is annular, the embroidery needle or needles may work through the open center of such flange so embroidering the desired figure on the fabric so held.

Various means may be employed for fastening down the free ends 7 of these members 3; but the particular spring clamping means shown is convenient and satisfactory for the purpose. Such spring clamping means comprises a pin 8 having a head 9; a sleeve 10 surrounding said pin and located between the plate 1 and the head 9; such sleeve 10 having a flange 11 resting upon the plate 1; a bushing 12 outside of the sleeve 10, and carried by the free end 7 of member 3; a spring 13 surrounding bushing 12 and between the free end 7 of member 3, and the head 9 of the pin 8; and a clamping spring 14 secured to the lower side of the plate 1 and having in it an aperture for the passage of the pin 8. The aperture in the spring 14 is only very slightly larger than the pin 8, and is set at a very slight angle to the axis of the pin 8, so that it tends to clamp said pin 8 and hold it frictionally against upward motion.

The plate 1 is further provided with a headed releasing pin, 15, for each spring 14, said pin working through a suitable aperture in the plate 1, having at its upper end a convenient head 16 and having at its lower end another head 17 resting against the end of the plate 14. It will be seen that, with the parts in the position shown in Fig. 2, slight pressure upon the head 9 of the pin 8 will force that pin down, through the aperture in the spring 14, and that such spring 14 will hold the pin 8, frictionally, against return; but that pressure upon the head 16 of the releasing pin 15 will depress the spring 14 sufficiently to bring the axis of its aperture substantially coincident with the axis of the pin 8, thereby permitting the spring 13 (which spring was compressed by pressing the pin 8 downward) to force pin 8 upward. In practice, when the releasing button 16 is pressed, the spring 13, aided by the spring action of member 3, forces the pin 8 up far enough to clear the spring 14 altogether.

The sleeve 10 forms a guide for the pin 8, and also forms a stop to limit the extent of depression of that pin. Said sleeve 10 has in it a slot 18 in which works a pin 19 projecting from pin 8, whereby when the corresponding member 3 is raised, said sleeve 10 is prevented from dropping off the pin 8. The bushing 12 centralizes the spring 13, and also forms means for communicating downward motion of the head 9 of pin 8 to the free end 7 of member 3.

The spring clamping means just described forms a very compact, easily operated, easily released, and positive friction lock or clamp for the member 3.

As a convenient means for gaging the proper position of the pieces of fabric, I have provided the plate 1 with a gage plate 20, having in it V-shaped recesses 21 adapted to receive the corners of the fabric; said gage plate 20 pass screws 23 by which the gage plate is secured to the plate 1. It will be seen that the screws 23 and slots 22 permit the gage plate to be set at various distances from the apertures 2.

The manner of using the improved spanning frame will now be apparent. At the right of Fig. 1 I have shown a piece of fabric in place in the frame and held between the sides of one of the apertures 2 and the flange 4 of the corresponding member 3. In spanning such a piece of fabric, the corner of the fabric is set into the corresponding V-shaped recess of the gage plate 20, with the fabric spread across the aperture 2, and the remainder of the fabric laid to one side of the hole in plate 1 through which the pin 8 is to pass; the member 3 is then brought down, its flange 4 pressing the fabric against the sides of the aperture 2, and stretching the fabric tightly; the member 3 being then secured by pressing down the pin 8, such pin being held when so pressed down, by the clamping spring 14. Other pieces of fabric are spanned in the same manner, under successive members 3. When it is desired to release the pieces of fabric from the spanning frame, the several releasing buttons 16 are pressed, and as each button is pressed its corresponding member 3 flies upward, releasing the fabric.

The degree of obliquity of the apertures in spring 14 through which the pin 8 passes, with reference to the axis of that pin, is so slight that I have indicated it in Fig. 7 by showing in dotted lines the axis of said aperture and the axis of the pin.

What I claim is:—

1. A spanning frame comprising a support having in it one or more spanning apertures, in combination with one or more spanning members, each such member having an annular flange adapted to enter one of said spanning apertures, and to clamp fabric between it and the sides of the corresponding spanning aperture, and means for securing the said spanning members to said support on opposite sides of the corresponding spanning apertures.

2. A spanning frame comprising a support having in it one or more spanning apertures, in combination with one or more resilient spanning members, each such member having an annular flange adapted to enter one of said spanning apertures, and to clamp fabric between it and the sides of the corresponding spanning aperture, and means for securing the said spanning members to said support on opposite sides of the corresponding spanning apertures.

3. A spanning frame comprising a support having in it one or more spanning apertures, in combination with one or more spanning members, each such member having an annular flange adapted to enter one of said spanning apertures, and to clamp fabric between it and the sides of the corresponding spanning aperture, each such spanning member hinged to said support on one side of the corresponding spanning aperture, and means for securing the said spanning members to said support on the opposite side of the corresponding spanning apertures. 70
4. A spanning frame comprising a support having in it one or more spanning apertures, in combination with one or more resilient spanning members, each such member having an annular flange adapted to enter one of said spanning apertures, and to clamp fabric between it and the sides of the corresponding spanning aperture, each such spanning member hinged to said support on one side of the corresponding spanning aperture, and means for securing the said spanning members to said support on the opposite side of the corresponding spanning apertures. 75
5. A spanning frame comprising a support having in it one or more spanning apertures, in combination with one or more spanning members, each such member having an annular flange adapted to enter one of said spanning apertures, and to clamp fabric between it and the sides of the corresponding spanning aperture, means for securing each said spanning member to said support on one side of the corresponding spanning aperture, and a friction clamp for securing each such spanning member to said support on the other side of the corresponding spanning aperture. 80
6. A spanning frame comprising a support having in it one or more spanning apertures, in combination with one or more resilient spanning members, each such member having an annular flange adapted to enter one of said spanning apertures, and to clamp fabric between it and the sides of the corresponding spanning aperture, means for securing each said spanning member to said support on one side of the corresponding spanning aperture, and a friction clamp for securing each such spanning member to said support on the other side of the corresponding spanning aperture. 85
7. A spanning frame comprising a support having in it one or more spanning apertures, in combination with one or more spanning members, each such member having an annular flange adapted to enter one of said spanning apertures, and to clamp fabric between it and the sides of the corresponding spanning aperture, means for securing each said spanning member to said support on one side of the corresponding spanning aperture, and a friction clamp for securing each such spanning member to said support on the other side of the corresponding spanning aperture. 90
8. A spanning frame comprising a support having in it one or more spanning apertures, a spanning member for each such aperture adapted to span fabric across the aperture, and means for holding each spanning member in place comprising a locking pin, a clamping member adapted to engage such pin frictionally, and means adapted to engage such clamping member to release the pin. 95
9. A spanning frame comprising a support having in it one or more spanning apertures, a spanning member for each such aperture adapted to span fabric across the aperture, and means for holding each spanning member in place comprising a pin mounted on the spanning member, a clamping spring having an aperture through which such pin passes, the sides of such last mentioned aperture adapted to engage and hold the pin frictionally, and releasing means adapted to engage such spring and thereby to release the pin. 100
10. A spanning frame comprising a support having in it one or more spanning apertures, a spanning member for each such aperture adapted to span fabric across the aperture, and means for holding each spanning member in place comprising a pin mounted on the spanning member, and adapted to pass through a corresponding aperture of said support, a clamping spring on the under side of such support having an aperture through which such pin may pass, the sides of such aperture of such clamping spring adapted to engage and hold the pin frictionally, and releasing means adapted to engage such spring and thereby to release the pin. 105
11. A spanning frame comprising a support having in it one or more spanning apertures, a spanning member for each such aperture adapted to span fabric across the aperture, and means for holding each spanning member in place comprising a pin mounted on the spanning member, and adapted to pass through a corresponding aperture of said support, a clamping spring on the under side of such support having an aperture through which such pin may pass, the sides of such aperture of such clamping spring adapted to engage and hold the pin frictionally, and releasing means comprising a pin mounted in a further aperture in said support, one end of said last mentioned pin adapted to engage such spring and depress it. 110
12. A spanning frame comprising a support having in it one or more spanning apertures, 115
13. A spanning frame comprising a support having in it one or more spanning apertures, 120
14. A spanning frame comprising a support having in it one or more spanning apertures, 125
15. A spanning frame comprising a support having in it one or more spanning apertures, 130

5 ertures, a spanning member for each such aperture adapted to span fabric across the aperture, and means for holding each spanning member in place comprising a sleeve 10 mounted in an aperture of such spanning member and resting upon such support, a pin slidably mounted within said sleeve and extending through an aperture in said support, means for communicating pressure from said pin to said spanning member, said sleeve forming a stop for said pin, and a clamping spring beneath said support and having an aperture through which such pin passes, the sides of such last mentioned aperture adapted to engage and hold the pin frictionally.

15 13. A spanning frame comprising a support having in it one or more spanning apertures, a spanning member for each such aperture adapted to span fabric across the aperture, and means for holding each spanning member in place comprising a sleeve 20 mounted in an aperture of such spanning member and resting upon such support, a pin slidably mounted within said sleeve and extending through an aperture in said support, means for communicating pressure from said pin to said spanning member, said sleeve forming a stop for said pin, and a clamping spring beneath said support and having an aperture through which such pin passes, the sides of such last mentioned aperture adapted to engage and hold the pin frictionally, and means for actuating such clamping spring to release the pin.

25 14. A spanning frame comprising a support having in it one or more spanning apertures, a spanning member for each such aperture adapted to span fabric across the aperture, and means for holding each span-

ning member in place comprising a sleeve 30 mounted in an aperture of such spanning member and resting upon such support, a headed pin slidably mounted within said sleeve and extending through an aperture 35 in said support, a spring interposed between the head of said pin and the said spanning member and a clamping spring beneath said support and having an aperture through which such pin passes, the sides of such last mentioned aperture adapted to engage and hold the spring frictionally.

40 15. A spanning frame comprising a support having in it one or more spanning apertures, in combination with one or more spanning members, each adapted to span fabric across a corresponding aperture, and a spanning gage mounted on such support parallel with said spanning apertures and adjustable toward and from such apertures.

45 16. A spanning frame comprising a support having in it one or more spanning apertures, in combination with one or more spanning members, each adapted to span fabric across a corresponding aperture, and a spanning gage mounted on such support parallel with said spanning apertures and adjustable toward and from such apertures, such plate having V-shaped recesses, each 50 opposite one of said apertures in the support.

55 In testimony whereof I have signed this specification in the presence of two subscribing witnesses.
